SWINGING DOOR.

1,160,676.

Specification of Letters Patent.

Patented Nov. 16, 1915.

Application filed December 21, 1914. Serial No. 878,253.

To all whom it may concern:

Be it known that I, UUNO E. TUOMI, a subject of the Emperor of Russia, residing at Kansas City, in the county of Jackson 5 and State of Missouri, have invented certain new and useful Improvements in Swinging Doors; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to swinging doors, and more particularly to a door of that class which is hingedly mounted to swing in either direction, the object of the present invention being to provide a hinge which will 20 allow the door to not only swing in either direction but also to swing in either direction and from either vertical edge.

In accomplishing this object I have provided improved details of structure, the preferred forms of which are illustrated in the 25 accompanying drawings, wherein:—

Figure I is a perspective view of a door frame and door equipped with a hinge in accordance with my invention. Fig. II is a 30 plan view showing the door closed in full lines and indicating the double swinging movement in dotted lines. Fig. III is a detail perspective view of the hinge floor plate. Fig. IV is a detail perspective view of the 35 bottom corner hinge. Fig. V is a longitudinal section of the same. Fig. VI is a horizontal section of the same. Fig. VII is a longitudinal section of the upper corner hinge and its rail. Fig. VIII is a bottom 40 corner perspective of a part of the door and the lower corner hinge. Fig. IX is a detail perspective of the lower corner hinge barrel. Fig. X is a similar view of the lower corner hinge plunger.

45 Referring more in detail to the parts:— 1 designates a door frame and 2 a door that is mounted in the frame with the usual snugness but adapted for swinging in either direction and from either edge by reason of 50 its equipment with my improved hinge.

Fixed to the floor directly within the side members of the door frame are arcuatile floor plates 4 having upwardly facing grooves 5; the groove in each of the floor 55 plates being concentric with a central point in the other floor plate, each of said floor

plates having a central socket 6 and the groove in each plate being concentric with the socket and groove of the opposite plate.

The groove in each plate comprises a base 60 portion and an upper portion which are formed by providing the arcuatile shelves 8 at the sides of the base groove members, and the shelves 8 are curved outwardly at the ends in order to form the mouths 9 for receiving the hinge plungers and guiding the same to the grooves, as will presently be described.

Fixed in a mortise groove in each lower corner of the door is a bracket 11 comprising a base plate 12 and a spaced plate 13, which latter is provided with the end legs 14 that space the body portion from the plate 12 and with a hook 15 which is adapted for taking into a slot 16 in a key plate 17 that is 75 fixed to the door at the base of the mortise.

The outer end of the base plate 12 is provided with an opening 18 which is adapted to align with the groove in the floor plate; the body 12 being preferably enlarged at 80 that point to accommodate the opening which is of substantial size relative to the width of the body plate. The base plate 12 is also provided with side screw holes 20 in order that the bracket may be fastened in a 85 metal door.

Loosely mounted within the bracket 11 and projected beneath the body plate 12 of each of the corner hinges is a barrel 22, preferably square in cross section and adapted 90 to fit snugly within the upper groove member in the floor plate and rest upon the shelves 8 that form the lower groove in said plate, so that while the barrel may travel freely through the plate groove when the 95 door is swung it is held against rotation by its engagement with the sides of the groove.

The barrel 22 is provided at its inner corners with ribs 23 that are adapted for seating within the sockets 26 in the head 25 100 of a spring rod 24 that lies within the bracket 11, so that the rods may pivot on the ribs as presently described. The rod 24 terminates a short distance from the inner leg 14 of the spaced bracket member and carries a 105 spring 28 which bears against the shoulders 29 of the rod head 25 and at its inner end against a disk 30 that is threaded on a screw 31 that is carried on the inner leg 14 and is spaced from the end of the spring rod so 110 that the spring may have free lateral movement between the rod and screw. The disk

30 is provided with peripheral sockets 32 for receiving a tool by which the disk may be adjusted to vary the tension of the spring.

Fitting within the barrel 22 is a plunger 34 which is adapted to turn within the barrel 5 and has a socket 35 in its lower end for carrying an anti-friction bearing member 36. The bearing member 36 has an axis 37 the ends of which project into vertical slots 38 10 in the plunger so that the bearing member may have limited travel longitudinally within the plunger, but said member is normally tensioned to its outermost position by a spring 39 which is located within the socket 15 and seats against the anti-friction member to project said member.

The upper end of the plunger has a shank 40 which is riveted in the bracket member 18 and the lower end of the plunger projects beyond the end of the barrel 22 and is adapted for fitting snugly within the lower groove member of the floor plate, so that the bearing member may travel along the bottom of the groove and may, when it reaches 25 the center of the plate, be projected into the socket 6 therein.

The plunger 34 has flat sides 43 which bear against the sides of the groove in the face plate when the plunger is moved therethrough, and curved edges 44 that fit snugly 30 against the inner face of the barrel and are adapted for turning in a socket 45 that is formed by cutting back the shelves 8 that mark the upper groove member in the floor 35 plate, so that while the plunger may travel freely through the small base groove when fitted into the groove its narrow way it cannot turn in the groove until it reaches the socket position. It is apparent, however, 40 that with the socket 45 of sufficient diameter to receive the plunger on its long axis, the plunger may pivot when in the socket position but that when turned with its long axis out of the circumferential plane of the 45 groove it will lock in place until turned back to its original position relative to the groove. This potentiality of the plunger enables me to secure an anchorage for the hinge at either lower corner of the door, so that when 50 the door is opened from one edge the hinge will lock and operate at the other edge. The upper corners of the door have mortised grooves within which are fixed brackets 46, each of which contains a plunger comprising 55 a socket member 47 having a socket 48, containing a spring 49 and an anti-friction bearing 50 having an axle 51 slidably mounted in slots 52 in the sides of the socket member and urged outwardly by the spring so that 60 it may travel in an upper groove plate 54 that is mortised into the upper portion of the door frame and serves to complement the lower corner hinge.

In using the hinge, assuming the lower 65 and top frame plates to be arranged as de-

scribed and the corners of the door provided with the proper hinge parts, the door is held in place by the plunger and groove parts on the door frame and door respectively. To open the door it is only necessary to push 70 on either of the vertical edges so that the door may pivot on the corner hinges at its opposite edge. When the edge of the door is pushed the anti-friction member in the plunger at the moving edge rides out of the 75 socket in the floor plate onto the base of the groove and the plunger moves through the groove until it leaves the floor plate, the bearing member in the upper plunger also being pressed out of its socket so that its 80 plunger may travel through the groove in the upper plate in the same manner as the like parts in the floor plate. As the free edge of the door moves open the opposite edge pivots to permit the open travel so 85 that the hinge bracket turns on the barrel 22 which is held against revoluble movement in the floor plate; the socket member 34, however, being fixed to the bracket member is turned therewith so that the longer axis of 90 the plunger is moved into the socket 45 in the groove shelves 8 and effectually locks the pivoting hinge against circumferential travel in the floor plate.

It is apparent that with the hinge locked 95 as described the door may turn freely on such hinge, and that as it opens it exerts an increased tension on the spring 28 which tends to return the door to its original position when released. When the door is released the spring throws it back to its center, and as the door closes the pivoting plunger is turned within the larger socket until the long axis is again concentric with the opposite hinge point when the plunger 100 is free to travel in its groove should the door be pushed from that side, so that it may swing on its opposite pivot. It is apparent that while the door may swing freely from either side there is no possibility of its 105 escaping from its mounting, as the hinge, floor and upper frame plates are curved so that the plungers on opposite sides of the door cannot move therethrough simultaneously and the pivoting plunger is locked 110 to its floor plate when the opposite edge of the door is in open position.

Having thus described my invention, what I claim as new therein, and desire to secure by Letters-Patent, is:—

1. The combination with frame and door members, one having a grooved plate at each corner position and the other having relative plunger members, each plate having a stepped groove therein and having a base socket, the step portion of the groove having socketed parts concentric with the base socket, each plunger comprising a barrel member slidably mounted in the plate groove and movable on the seat portion 125 130

without pivotal movement, and a plunger slidably mounted in the base portion of the groove, and adapted for pivoting in the socketed part of the seat portion, the barrel being pivotally connected with its carrying member and the plunger fixed thereto for the purpose set forth.

2. The combination with door frame and door members, one having a grooved plate at each corner position and the other having relative plunger members, each plate having a stepped groove therein and having a base socket, the seat portion of the groove having socketed parts concentric with the base socket, each plunger comprising a barrel member slidably mounted in the plate groove and movable on the seat portion without pivotal movement, and a plunger slidably mounted in the base portion of the groove and adapted for movement in the socketed part of the seat portion, the barrel being pivotally connected with its carrying member and the plunger fixed thereto, spaced ribs on said barrel, a rod having a head provided with sockets for turning on the barrel ribs and yielding means connecting the rod with its carrying member.

3. The combination with a door frame and door, of a plate fixed to opposite sides of the door frame and having concentric grooves therein, seats in each of the plate grooves forming shelves concentric with the sides of the base grooves, said shelves having concentric facing sockets, a bracket fixed to each corner of the door, a barrel pivotally mounted in each bracket and having a projecting portion slidably mounted in a relative plate groove, whereby the barrel may travel through the groove without pivotal movement, a plunger pivotally mounted in said barrel and fixed to the bracket, the said plunger being slidably mounted in the base plate groove and adapted for pivoting in the shelf socket.

4. The combination with a door frame and door, of plates fixed at opposite sides of the door frame and having concentric grooves therein, seats in each of the plate grooves, forming shelves, said shelves having concentric facing sockets, a bracket fixed to each corner of the door, a barrel pivotally mounted in each socket and having a projecting portion slidably mounted in a relative plate groove, whereby the barrel may travel through the groove without pivotal movement, a plunger pivotally mounted in said barrel and fixed to the door, the said plunger being slidably mounted in the base plate groove and adapted for pivoting in the shelf socket, and an antifriction member carried by said plunger and adapted for travel on the base of the plate groove.

5. The combination with a door frame and door, of plates fixed to opposite sides of the door frame and having concentric grooves

therein, seats in each of the plate grooves, forming shelves, having concentric sockets, a bracket fixed to each corner of the door, a barrel pivotally mounted in each socket and having a projecting portion slidably mounted in a relative plate groove, whereby the barrel may travel through the groove without pivotal movement, a plunger pivotally mounted in said barrel and fixed to the door, the said plunger being slidably mounted in the base plate groove and adapted for pivoting in the shelf socket, and an antifriction member carried by said plunger and adapted for travel on the base of the plate groove, the said plate groove having a base socket concentric with the step sockets for receiving the antifriction member to anchor the plunger to the plate for the purpose set forth.

6. The combination with door frame and door members, of facing plates fixed to the door frame members at each side of the frame the upper and lower plates on opposite sides of the frame having concentric grooves therein, and having spaced steps forming relatively wide upper and narrow base grooves, each plate having a central socket and the steps having sockets concentric with the base socket, a bracket fixed to each corner of the door, and adapted for travel over a relative grooved plate, a barrel pivotally mounted in each bracket and having a squared portion adapted for travel through its relative plate groove without pivotal movement, a plunger, oblong in cross section, pivotally mounted in each barrel, the lower end of the plunger being projected beyond the barrel and adapted for sliding travel in the base plate groove, while the ferrule travels in the upper plate groove, the plunger being adapted for travel through its groove along its short axis and for pivotal movement in the seat sockets along its long axis, an antifriction member carried by the plunger and adapted for seating in the base sockets in the plate groove, and yielding means for normally retaining the door in closed position.

7. The combination with an anchor plate having a groove therein, of steps at opposite sides of the groove having facing sockets concentric with the groove, a barrel pivotally mounted in the door bracket and having a squared end slidably mounted in the plate groove and upon the stepped part thereof, a plunger fixed to the door and pivotally mounted in said barrel, the plunger having flattened sides and being projected into and adapted for travel in the base groove in the plate and for pivotal movement in the barrel and in the step portion of the grooved plate.

8. The combination with an anchor plate having a groove therein, of steps at opposite sides of the groove having facing sockets concentric with the groove, a barrel piv-

totally mounted in the door bracket and having a squared end slidably mounted in the plate groove, and upon the stepped part thereof, a plunger fixed to the door and pivotally mounted in said barrel, the plunger having flattened sides and being projected into and adapted for travel in the base groove in the plate and for pivotal movement in the barrel and in the stepped portion of the grooved plate; the said plate having a base socket concentric with the step sockets and the plunger having a downwardly opening socket, an antifriction member mounted in said plunger and adapted for seating in the base member in said plate, and a spring in the plunger socket engaging the antifriction member to urge the same to its seat in said base socket.

9. The combination with a fixed frame plate having an arcuatile groove, steps at the sides of the groove forming base and upper guides, of a door bracket, a barrel pivotally mounted in said door bracket and adapted for travel in the upper plate guide, a plunger fixed to the bracket and adapted for travel in the lower plate guide, the plunger having a long and a short axis and the step portion of the guide plate having facing sockets whereby the plunger may travel through the plate groove without pivotal movement and may pivot in the step sockets substantially as set forth.

10. The combination with door frame and door members, of a plate fixed to each corner of the frame and having an arcuatile groove therein, seats in the plate groove forming upper and lower guides, a plate fixed to each corner of the door, a bracket removably mounted on said plate, a barrel pivotally mounted in the bracket and having a squared portion slidably mounted in the outer plate guide and on the step therein, a plunger fixed to said bracket and pivotally mounted in said barrel, the plunger having flattened sides and projecting from the barrel to travel in the inner plate guide, the plate step having facing sockets forming a pivoting enlargement for the plunger, a rod having rocking contact with the barrel, a keeper on said bracket and spaced from the end of the rod opposite the barrel, and a spring inclosing the rod and bearing against a part of the rod and against said keeper for the purpose set forth.

11. The combination with a frame plate having concentric, arcuatile upper and lower grooves of different widths, of a door

bracket, a barrel pivotally mounted on the door bracket and adapted for travel in one of the grooves, a plunger fixed to the bracket and pivotally projected through the barrel and adapted for travel in the other plate groove, the plate having a socket portion and the plunger being oblong in cross section to slide through its groove without pivotal movement and to turn in said socket, a member carried by the bracket and rockable on the barrel, and a spring connecting the rod and bracket for the purpose set forth.

12. The combination with a door, of a fixed hinge plate having an arcuatile stepped groove and having concentric sockets in the grooved steps, a hinge member fixed to the door and comprising a barrel adapted for guided travel in one of said grooves, a plunger fixed to the door member and adapted for guided travel in the other hinge member and for pivotal movement in the larger socket, an anti-friction member slidably mounted in the plunger and adapted for seating in the smaller socket, means for yieldingly tensioning said anti-friction member to its seat, and a spring mounted in the door hinge member and anchored to said barrel.

13. A swinging door hinge comprising a stationary hinge plate, having an arcuatile groove offset at its open side to form shelves and having a socket in the base of the groove and cavities in the shelves concentric with the base groove, a door hinge member, a barrel loosely mounted in said member and having locking anchorage therein, one end of the barrel being squared and projected into the offset portion of the groove in the fixed plate to permit said barrel to travel in the groove without pivotal movement, a plunger fixed to the door hinge member and having flat faces for guiding engagement with the base groove and curved edges adapted for permitting pivotal movement of the plunger in said recesses, a tumbler in said plunger adapted for taking into the base socket, a rod having a head engaging the barrel and a keeper member in the door hinge member, and a spring surrounding the rod and engaging the keeper member and rod head.

In testimony whereof I affix my signature in presence of two witnesses.

UUNO E. TUOMI.
